UNITED STATES PATENT OFFICE.

SAMUEL A. JESSUP, OF CHARLOTTESVILLE, VIRGINIA.

DESIGN FOR A BOTTLE.

Application filed November 26, 1926. Serial No. 19,845. Term of patent 7 years.

To all whom it may concern:

Be it known that I, SAMUEL A. JESSUP, a citizen of the United States, residing at 4th and Water Sts., city of Charlottesville, in the county of Albemarle and State of Virginia, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

SAM. A. JESSUP.
